UNITED STATES PATENT OFFICE.

ALLEN CLYMER AUSTIN, OF SYRACUSE, NEW YORK.

PRESSING-MACHINE.

1,252,988.

Specification of Letters Patent.

Patented Jan. 8, 1918.

Application filed October 5, 1915. Serial No. 54,149.

To all whom it may concern:

Be it known that I, ALLEN CLYMER AUSTIN, a citizen of the United States, and a resident of Syracuse, in the county of Onondaga and State of New York, have invented a certain new and useful Pressing-Machine, of which the following is a specification.

My invention relates to pressing machines, of the class described in the pending application of F. A. Austin and myself, Sr. No. 855,549, filed Aug. 7, 1914, and has for its object the production of a machine which is particularly simple and economical in construction and highly efficient, durable, and economical in use; and it consists in the combinations and constructions hereinafter set forth and claimed.

One object of the invention is the production of a system of connecting the interiors of the upper and lower pressing elements or bucks to a steam supply, by which the bucks are kept hot at a comparatively low steam pressure.

Another object of the invention is the construction of a particularly efficient means for connecting one of the bucks, usually the upper buck, to its support or carriage so that rocking movement of the buck in a plurality of directions relatively to its carriage is permitted. Another object is the production of steam connections for the movable buck, which include a flexible coupling facilitating the various movements of the upper buck.

35 Other objects will appear throughout the specification.

In describing this invention reference is had to the accompanying drawings, in which like characters designate corresponding parts in all the views.

Figure 1 is a side elevation, partly in section, of my pressing or ironing machine.

Fig. 1^a is a detail view, partly in section, of the toggle link and contiguous parts.

45 Fig. 2 is a plan view of parts seen in Fig. 1, parts being omitted.

Fig. 3 is a horizontal sectional view through the lower buck.

50 Figs. 4, 5, and 6 are sectional views taken respectively on the planes of lines 4—4, 5—5, and 6—6, Fig. 3.

Fig. 7 is a sectional view on line 7—7, looking to the left, in Fig. 3, the distributing plate or strip being omitted.

55 Fig. 8 is a vertical sectional view through the upper buck.

Fig. 9 is a sectional view on line 9—9, Fig. 8.

Fig. 10 is an enlarged sectional view taken on the plane of line 10—10, Fig. 1.

Fig. 11 is an elevation looking to the right in Fig. 10, parts being omitted.

Fig. 12 is a fragmentary view, illustrating in plan and partly in section, the front end of the operating lever.

Fig. 13 is a fragmentary plan view of the lower buck showing the distributing plate or strip thereon.

Fig. 14 is a detail view of the distributing strip.

This pressing machine comprises, generally, a frame, pressing elements usually called bucks, one as the lower buck being mounted on the frame, and the other as the upper buck being movable toward and from the lower buck, a movable carriage in the form of a frame lever carrying the upper buck, and operating means for the movable carriage.

1 designates the frame which may be of any suitable form, size and construction, it being here shown as consisting of a table 2, three legs 3 supporting the table, two legs being arranged at the front side of the frame, and the third leg on the rear side thereof being arranged midway between the sides of the machine, and a bracket 4, continuing upwardly from the rear leg 3.

5 is a bracket mounted on the table, and 6 is the lower buck mounted on the bracket 5.

The lower buck 6 is formed with a plurality of chambers arranged side by side and connected in series, with their tops in the same plane when the upper face of the buck is flat, or continuous if the face of the buck 95 is convex. In this embodiment of my invention the lower buck is formed with two lengthwise chambers 7, 8 which are comparatively wide and shallow, and with a central elongated chamber 9 in the form of a 100 conduit located between the chambers 7, 8, and preferably having its side and bottom walls exposed in the chambers 7, 8 so as to be nearly surrounded by the steam in the chambers 7, 8. The chambers 7, 8 are connected in series with each other as by a 105 passage 10 at one end of the buck (Figs. 3 and 4).

11 is an inlet conduit for the steam which extends vertically through the bracket 5, 110 upwardly through the bottom of the lower buck 6, and into one end of the chamber

7 or the first of the pair of chambers 7, 8. 12 is an outlet leading from the corresponding end of the second chamber 8 of the pair, downwardly through the buck and into a 5 receiving chamber 13 preferably located within the bracket 5. The inlet 11 and outlet 12 are located remote from the passage 10 connecting the chambers 7, 8, and deflectors 12^a are located near the passages 11, 10 12, to insure a complete distribution of the steam.

14 is a conduit, Figs. 4 and 7, communicating with the receiver 13 and opening into the chamber 9, said conduit being located 15 partly in the lower buck and partly in the bracket 5.

15 is a passage or conduit leading from the receiver 13 in the bracket 5. 16, Fig. 1, is a valve casing, connecting the passages or 20 conduits 14, 15, in which casing, a suitable valve is located for controlling the flow of steam to the chamber 9, this valve being operated by a rod 17 extending downwardly to the base of the machine and actuated as 25 hereinafter described.

The lower buck is preferably cast in one piece so that no separate top or top plates are necessary, and hence machining and fitting of parts are avoided. As seen in Figs. 30 5, 6 and 7, the chambers 7, 8 gradually deepen along the course taken by the steam from the inlet 11 to the outlet 12, the chamber 7 deepening from the inlet 11 and the chamber 8 deepening in the opposite direction toward the outlet 12, so that any water appearing in said chambers will drain into the receiver 13. The top of the chamber 9 is perforated at 18, Fig. 4, and a distributing plate or strip 9^a overlies the perforations, and serves to distribute the steam ejected from the perforations over the entire effective surface of the buck so that the steam passes through all portions of the garment being pressed, Figs. 13 and 14. Said 40 strip is here illustrated as formed with a lengthwise corrugation 9^b disposed over the line of perforations and with transverse corrugations 9^c, for facilitating the distribution of the steam. The transverse corrugations 45 9^c lead from the lengthwise corrugation 9^b to the lengthwise edges of the distributing plate at an angle thereto, and, consequently, the steam escapes between spaced apart surfaces of the lengthwise edges of the distributing plate and the underlying portion 50 of the lower buck. The strip 9^a is secured to the buck in any suitable manner as by clenching its ends over the ends of the buck but may be secured to a wire gauze overlying the face of the buck beneath the felt padding 6^a.

An inlet pipe 19 for the lower buck is connected to the outlet pipe of the upper buck, and an outlet, drain, or return pipe 20 65 is connected to the receiver 13.

The steam passes into the chamber 7 through the inlet conduit 11, along the chamber 7 through the passage 10 into the chamber 8, lengthwise of the chamber 8 through the outlet conduit 12, to the receiver 13 70 where any water of condensation is deposited and carried off through the pipe 20; and when the rod 17 is operated to open the valve within the casing 16, the steam, from which the water has been removed, passes 75 through the passage 15, valve casing 16, and passage 14 to the central chamber 9, where it is ejected through the perforations or jets 18. The steam in the chamber 9 is heated by the hot live steam in the chambers 7, 8, 80 so that condensing of the steam in the chamber 9 and hence the ejection of water through the perforations 18 is prevented. A suitable deflector 22 is located in the receiver 13, see 85 Figs. 6 and 7, between the conduit 12 and the passage 15, this deflector causing the steam to circulate in the receiver instead of being permitted to pass directly out of the passage 15 to the chamber 9. In use the receiving chamber remains partly filled with 90 the water of condensation so that the steam will not pass through the drain pipe but on the contrary is withdrawn through the passage 15 above the level of the water of condensation. 95

23 is the upper buck which is movable toward and from the lower buck. 24 is the carriage for the upper buck, said carriage being a frame lever pivoted between its ends to the bracket 4 and carrying the buck 23 100 on the front arms thereof. The buck 23, Figs. 8, 9, is also cast in one piece and is formed with two lengthwise chambers 25, 25^a located different distances from the axis of the carriage 24, said chambers being in 105 communication with each other at 26 near one end of the buck 23. 27 is a steam inlet pipe section arranged at the opposite end of the buck 23 and extending radially relatively to the axis of the carriage 24 and 110 through the chamber 25^a and the partition separating the chambers 25, 25^a and opening into the chamber 25 near the end thereof remote from the passage 26. 28 is the outlet pipe leading from the chamber 25 from the point thereof nearest the axis of the frame lever 24. The pipes 27, 28 are preferably arranged concentric with each other and the inlet pipe 27 is located within the outlet pipe 28. Owing to this arrangement of the chambers 25, 25^a, and the pipes 27, 28, any water of condensation in the upper buck will drain out through the outlet pipe and pass into the receiving chamber 13 when the buck is moved into its upper position from that 115 shown in Fig. 1. 120

The walls of the chamber 9, the deflectors 12^a, the partition between the chambers 25, 25^a of the upper buck, and the inlets and outlets for the bucks located as described, 125 130

constitute, in a broad sense, means for causing the heating medium as steam to travel or circulate in a single path longitudinally of the bucks so that all portions 5 of the faces of the bucks are of uniform temperature; and the chambers 7, 8 of the lower buck constitute means for heating the chamber 9 (from which the steam is ejected through the garment) on opposite sides of 10 said chamber 9.

The frame lever 24 is bifurcated, that is, it includes two branches or arms 29 and these arms are provided with bearings 30 on a pivot pin 31 supported at the upper end 15 of the bracket 4, the arms 29 diverging toward their front ends.

The portions of the arms or branches 29 of the frame lever 24 in the rear of the pivot 31 are connected by a web 32, see Fig. 2. Bracket arms 33 extend forwardly from the front ends of the arms 29 of the frame lever 24, and support a suitable handle 34 by means of which the upper buck may be 20 pulled downwardly.

25 The upper buck 23 is yieldingly carried by, or suspended from, its carriage, that is the frame lever 24, and it is here shown as suspended from the carriage at three points by pins 35 and springs 37, the pins rising 30 from the top of the buck 23 and sliding through perforations in lugs 36, 36^a provided in the arms 29, and having shoulders as nuts 38 at their upper ends. The springs 37 are compressed between the upper sides of 35 the lugs 36, 36^a and the shoulders 38. Suitable caps 37^a inclose the springs 37. The upper buck 23 and its carriage 24 are provided with two sets of bearing parts located at the ends of the arms 29 and midway between the front and rear edges of the upper buck 23, the bearing parts being constructed to permit a rocking movement about an axis extending lengthwise of the buck 23 or parallel to the axis of the carriage 24, 40 and also about axes extending through the sets of bearing parts and at an angle with the former axis. 39 and 40 or 39^a and 40^a are the bearing parts of each set which are associated respectively with the contiguous 45 arm 29 of the carriage 24 and with the buck 23 and are separable from each other, separation of these bearing parts and also rocking movement of the buck about its axes being resisted by the springs 37. These 50 bearing parts as here shown, consist of a knife edge or wedge and a notch receiving the knife edge, each knife edge or wedge being arc-shaped or curved as indicated at 41, 41^a, Fig. 8, in a direction lengthwise 55 thereof. The notches and knife edges are arranged in the line of the longitudinal axis of the upper buck 23. The lugs 36 at one end of the buck extend forwardly and rearwardly from the bearing part 39 and 60 two of the points of suspension of the buck

23 are arranged respectively in front of, and in the rear of, the bearing parts 39, 40. The third point of suspension is arranged in line with the common axis of the bearing parts, the lug 36^a extending laterally from the bearing part 39^a. Owing to the three point suspension of the buck 23, and the arrangement of the bearings thereof, the buck can yield about its longitudinal axis and also about the axis of either one of the 70 arc-shaped knife edges of the bearing parts 39, 39^a, this yielding being effected by any unevenness in the thickness of the garment or other article being ironed. The bearing parts 39, 40 and 39^a, 40^a form practically 75 two universal joints, the members of each of which separate when the other is operating in a certain direction. For instance, the members 39, 40 separate when the buck moves about an axis passing through the 80 members 39^a, 40^a at an angle to the lengthwise axis of the buck. Such separation would take place when the garment is 85 thicker at one end than at the other.

The inlet pipe section 27 is connected to 90 a feed pipe section 42 and the outlet pipe section 28 to a pipe section 43, by a flexible coupling 44 extending radially from the pivot 31 of the frame lever 24.

This coupling 44 comprises unions 45, 46, 95 and side pieces 47, 48 connecting the unions. The union 45 is located at the axis of the frame lever 24 and is provided with radial nipples 49, 50 for receiving the pipes 42, 43 respectively, said nipples 49, 50 being here 100 shown as arranged at a right angle to each other, the union 45 being also provided with axial passages 51, 52, extending lengthwise of the axis of the frame lever 24 and opening through opposite ends of the union and 105 into the nipples 49, 50 respectively, said passages 51, 52 being separated from each other by an inclined partition 53.

The union 46 is also formed with a radially extending nipple 55 which is an integral part of the pipe section 28, and also with axially extending passages 56, 57 opening through opposite ends thereof and separated by a radially extending partition 58, the passage 56 being connected to the pipe 110 section 27 by an internally threaded bore. The side-pieces 47, 48 are alike in construction and are formed with nipples or hubs 59 at their opposite ends which fit over the opposite ends of the unions 45, 46, suitable 115 packings 60 being interposed at the joints between the side pieces and the unions.

The side pieces 47, 48 are formed with passages 61, 62 which connect respectively with the passages 51, 56, and 52, 57, of the 120 unions. The side pieces are clamped together by suitable bolts 63 located between the unions 45, and 46. The pipe 43 is connected to the inlet pipe 19 for the lower buck and is also connected to the drain or return 130

pipe 21 through a valve 43^a which is normally closed.

In operation the steam passes from the pipe 42 to the passage 51 and through the 5 passages 51, 61, 56, and the pipe 27 into the chamber 25 of the upper buck, through the chamber 25, the passage 26 and the chamber 25^a and out through the pipe 28 to the nipple 55, thence through the passages 57, 62 10 and 52 to the return pipe 43, thence through the inlet pipe 19 for the lower buck, passage 11, chambers 7, 8 and passage 12 of the lower buck, to the receiver 13 where the water is deposited. Upon the opening of the 15 valve in the chamber 16, the steam passes from the receiver to the chamber 9, through the passages 15, 14, and is ejected through the perforations 18 and distributed over the effective pressing area of the buck by the 20 distributor 9^a. From the foregoing it will be apparent that the interiors of the buck are connected in series and that a receiver or condensing chamber 13 is located in the steam circuit between the upper buck and 25 one of the chambers of the lower buck. Owing to the arrangement of the steam connections of the upper and lower bucks, pressure is equalized in the chambers of the bucks, the entire utilized volume of heating 30 medium or steam passes successively through both pressing elements or bucks, and all water is removed or reconverted into steam before the steam reaches the jets 18.

The means for operating the carriage 24 35 of the upper buck comprises power transmitting parts including a yielding or spring connection. As here illustrated said means comprises an angle lever 64 pivoted at 65 to the frame, near the bottom thereof and 40 formed with a forwardly extending arm 64^a provided with a suitable pedal 66, and with an upwardly and rearwardly extending arm 64^b, and a toggle link interposed between the latter arm 64^b and the rear arm 45 of the frame lever 24, said link including the yielding or spring power transmitting part. Preferably, this toggle link includes sections 67, 68, 69, and the spring means. The member or section 67 is pivoted at 67^a to the rear 50 arm of the lever or carriage 24; the member or section 68 is a shackle or clevis pivoted at 68^a to the lever 64; and the member or section 69 is a rod slidable endwisely of one of the sections 67, 68 as the section 68, and 55 adjustable endwisely relatively to the other section 67. The section 69 is here shown as a screw which threads into the part 67 and slides in the shackle 68, the sliding movement being resisted by a spring 70, the screw 60 having a head 71 engaging the shackle to prevent detachment of the section 69 from the shackle.

The endwise adjustment of the section 69 relatively to the section 67 to lengthen or 65 shorten the toggle link, comprises means for

rotating the screw section 69, and this means is here illustrated as a nut 72 located on the screw 69 and locked in position by a nut 73. The nut 72 also forms an abutment for one end of the spring 70 which encircles 70 the screw and abuts at its other end against the shackle. Movement of the nut 72 on the screw 69, after the lock nut 73 is loosened, adjusts the tension of the spring 70, and turning of the nut 72 without loosening the 75 nut 73, causes the screw 69 to turn in the section 67, and hence to lengthen or shorten the toggle link.

When the upper buck is down, the rear arm of the frame lever 24 is in a horizontal 80 position as shown in Fig. 1, and the coil spring 64^a, Fig. 1, connected to the forwardly extending arm 64^a of the lever 64, tends to hold the parts in the position shown in Fig. 1, and the toggle joint 68^a is in the dead 85 center line of the toggle. Upward movement of the buck is facilitated after the toggle joint 68^a has been moved out of its center line, as will be presently described, by a counter weight 74 mounted on the pivot 90 67^a and having a pair of forwardly extending arms 75 which press at their front ends against the under side of the web 32 of the frame lever or carriage 24. Owing to the spring 70, the toggle joint is permitted to 95 enter its dead center line irrespective of the thickness of the garment or other article being ironed between the upper and lower bucks, and furthermore the machine, owing to the spring 70, can be adjusted to suit the 100 strength of the operator, and the pressure of the upper buck can be regulated.

The movement of the toggle joint 68^a out of the dead center line is effected by means of a lever 76 pivoted at 77 to a suitable 105 bracket 78 and having one arm 79 thereof pressing against the under side of the forwardly extending arm 64^a, of the lever 64. Obviously when the front end of the lever 76 is depressed, the arm 79 will push upwardly on the forwardly extending arm 64^a of the lever 64 causing the lever to move, so that the joint 68^a of the toggle is carried rearwardly. The pedal 66 at the front end 110 of the lever 64 is a separate piece from the lever 64 and is connected thereto so as to be adjustable upwardly and downwardly thereon in any suitable manner, this adjustment being for the purpose of bringing the pedal 66 in proper relation to the floor or bed on 115 which the machine stands. As here shown, Figs. 1 and 12, the pedal 66 is pivoted at 80 to the front arm 64^a of the lever 64 and is held in any adjusted pivotal position by a bolt 81 passing through said front arm of 120 the lever 64 and a slot 82 in the pedal 66, and also by a tooth 83 on the pedal coating with one of a series of teeth 84 on the arm 64^a of the lever 64.

A suitable pedal is connected to the rod 17 125

which operates the valve in the casing 16, a portion of this pedal being indicated at 85.

The throw of the lever 64 and hence the movement of the toggle joint 68^a is limited by adjustable stops or buffers here illustrated as nuts 86 threading on a link 87, which is pivoted at 88 at one end to the lever 64 and is slid able in a pivoted bearing 89 in the frame 1. The bearing 89 is preferably mounted to rock during the movement of the link 87.

In operation the machine is arranged with the upper buck in its upper position so that a garment may be placed on the lower buck. 15 The pedal 66 is then depressed bringing the parts into their position shown in Fig. 1, and if it is desired to pass steam through the garment, the pedal 85 is operated permitting the steam to pass through the chamber 9 and perforations 18, and to be distributed over the faces of the bucks, the steam circulating through both bucks when the pedal 85 is operated. If the garment is of 20 different thicknesses the upper buck 23 yields to conform to the different thicknesses of the garment by reason of the bearing parts 39, 40 and 39^a and 40^a. The means, just described, for operating the carriage 24 is not claimed herein, as it constitutes the subject-matter of my pending divisional application Sr. No. 117,435.

What I claim is:

1. In a pressing machine, the combination of upper and lower fluid heated bucks having internal chambers, one of the bucks having a plurality of said chambers, the internal chamber of one buck and one of the plurality of chambers of the other buck being connected in series with each other, and 25 a valve controlled conduit connected between said plurality of chambers of one of the bucks, substantially as and for the purpose specified.

2. In a pressing machine, the combination of upper and lower fluid heated bucks having internal chambers, one of the bucks having a plurality of said chambers, the internal chamber of one buck and one of the plurality of chambers of the other buck being 30 connected in series with each other, and another of said plurality of chambers opening through the wall of the buck to the exterior thereof, and a valve controlled conduit connected between said plurality of chambers of one of the bucks, substantially as and for the purpose set forth.

3. In a pressing machine, the combination of upper and lower fluid heated bucks having internal chambers, one of the bucks having a pair of lengthwise chambers arranged side by side and connected in series, and a third lengthwise chamber located between the former chambers and disconnected therefrom, a part of the inclosing wall of 35 the third chamber being exposed in the pair

of chambers, the third chamber opening through the wall of the buck provided therewith to the exterior of said buck, and one of the pair of chambers being connected in series with the interior of the other buck, 70 and a valve controlled conduit connecting the other of the pair of chambers and the third chamber, substantially as and for the purpose described.

4. In a pressing machine, the combination of upper and lower fluid heated bucks having internal chambers, the lower buck having a plurality of said chambers, the internal chamber of the upper buck and one of the chambers of the lower buck being connected in series with each other, and another of the chambers of the lower buck opening through the wall of said buck to the exterior thereof, and a valve controlled conduit connected between the plurality of 80 chambers of the lower buck, substantially as and for the purpose specified.

5. In a pressing machine, the combination of upper and lower fluid heated bucks having internal chambers, the lower buck having a pair of lengthwise chambers arranged side by side and connected in series, and a third lengthwise chamber located between the former chambers and disconnected therefrom, a part of the inclosing wall of 90 the third chamber being exposed in the pair of chambers, the third chamber opening through the wall of the lower buck to the exterior thereof, and the internal chamber of the upper buck and one of the pair of 100 chambers being connected in series with each other, and a valve controlled steam supply connected to said third chamber, substantially as and for the purpose set forth.

6. In a pressing machine, the combination of upper and lower fluid heated bucks, having internal chambers, one of the bucks having a plurality of said chambers, the interior of one buck and one of the plurality of chambers of the other buck being connected in series with each other, and another of said plurality of chambers opening through the face of the buck to the exterior thereof, a valve controlled conduit connected between said plurality of chambers of 110 one of the bucks, and a receiver connected in said conduit, substantially as and for the purpose specified.

7. A pressing machine, comprising upper and lower fluid heated bucks having internal chambers, one of the bucks having a plurality of said chambers, one of said plurality of chambers being connected in series with the interior of the other buck and the other chamber being formed with a perforated top, a receiver connected in series with said one of the plurality of chambers, and a valve controlled conduit connecting the receiver and said other chamber, substantially as and for the purpose specified. 120 125 130

8. In a pressing machine, the combination of upper and lower fluid heated bucks, the lower buck having a plurality of chambers connected in series and a lengthwise chamber located between the former chambers and disconnected therefrom, a part of the inclosing wall of the third chamber being exposed in the former chambers and the third chamber opening through the wall of the lower buck to the exterior thereof, a receiver, conduit connections between the interior of the upper buck and the first of the pair of chambers of the lower buck, conduit connections between the second of the pair of chambers of the lower buck and the receiver, a valve controlled conduit between the receiver and the third chamber of the lower buck, and an outlet pipe leading from the receiver, substantially as and for the purpose described.

9. In a pressing machine, a buck formed with a pair of heating chambers arranged side by side and connected in series and with a third chamber separating the pair of chambers, and means for connecting the third chamber in series with the second chamber of the pair, substantially as and for the purpose described.

10. In a pressing machine, a buck formed with a pair of comparatively wide and shallow heating chambers and a comparatively narrow third chamber separating the former chambers, the chambers being connected in series, substantially as and for the purpose specified.

11. In a pressing machine, a buck formed with a pair of heating chambers connected in series and a third chamber in the form of a conduit located between and separating the pair of chambers, the third chamber having its side and bottom walls exposed in the pair of chambers, substantially as and for the purpose set forth.

12. In a pressing machine, a buck formed with a pair of heating chambers connected in series, and a third chamber in the form of a conduit separating the pair of chambers and heated thereby, the third chamber having passages opening through the wall of the buck to the exterior thereof, and a valve controlled steam supply for the third chamber, substantially as and for the purpose described.

13. In a pressing machine, a buck formed with a pair of heating chambers connected in series and a third chamber in the form of a conduit separating the pair of chambers, the third chamber having its side and bottom walls in common with the pair of chambers, the top wall of the third chamber being perforated, and means for connecting the third chamber in series with the second chamber of the pair of chambers, substantially as and for the purpose described.

14. In a pressing machine, a buck formed

with a plurality of heating chambers arranged side by side, a receiver, a feed pipe in communication with one chamber, a conduit connecting said chamber and the receiver, and a conduit connecting the receiver and the other chamber, substantially as and for the purpose specified.

15. In a pressing machine, a buck formed with a plurality of heating chambers arranged side by side, a receiver, a feed pipe in communication with one chamber, a conduit connecting said chamber and the receiver, and a valve controlled conduit connecting the receiver and the other chamber, the latter chamber having its top wall perforated, substantially as and for the purpose specified.

16. In a pressing machine, a buck formed with a pair of heating chambers connected in series and a third chamber in the form of a conduit separating the pair of chambers, the third chamber having its side and bottom walls exposed in the pair of chambers, the top wall of the third chamber being perforated, a receiver, a feed pipe connected to one of the pair of chambers, a conduit connecting the other of the pair of chambers and the receiver, and a valve controlled conduit connecting the receiver and the third chamber, substantially as and for the purpose set forth.

17. In a pressing machine, a buck formed with a pair of heating chambers connected in series and a third chamber in the form of a conduit separating the pair of chambers, the third chamber having its side and bottom walls exposed in the pair of chambers, the top wall of the third chamber being perforated, a receiver, a feed pipe connected to one of the pair of chambers, a conduit connected to the other of the pair of chambers and to the receiver, a valve controlled conduit connecting the receiver and the third chamber, and an outlet pipe leading from the receiver, substantially as and for the purpose described.

18. In a pressing machine, a one piece hollow buck provided with a hollow wall dividing the buck into two chambers, the hollow wall forming a third chamber, said two chambers being connected together in series, a feed pipe connected to one of said two chambers, an outlet pipe connected to the second of said two chambers, and means connecting the outlet pipe and the third chamber, the third chamber being provided with a perforated top, substantially as and for the purpose specified.

19. In a pressing machine, the combination of a feed pipe for a heating vapor, upper and lower bucks, each having an internal chamber for receiving the heating vapor, an outlet pipe, and a receiving chamber arranged between, and communicating with, the outlet pipe and the internal chambers of

the bucks, and containing during the operation of the machine said heating vapor, and the liquid of its condensation, substantially as and for the purpose described.

- 5 20. In a pressing machine, the combination of upper and lower bucks, each having an internal chamber for receiving the heating vapor, one of said internal chambers having perforations opening through the 10 face of the buck, a receiving chamber communicating with said internal chamber having said perforations, to discharge thereto and with another of said internal chambers to receive vapor therefrom, the connection between said receiving chamber and the internal perforated chamber opening from said receiving chamber above the level of the liquid of condensation therein, substantially as and for the purpose set forth. 15
- 20 21. In a pressing machine, the combination of upper and lower bucks, one having an internal chamber for receiving a heating vapor, and one of the bucks having a plurality of said internal chambers, and the internal chamber of one buck being connected in series with one of the internal chambers of the other buck, and a third chamber of the buck provided with said plurality of chambers discharging to the exterior of said buck, 25 a receiving chamber for containing, during the operation of the machine, said heating vapor and the liquid of its condensation, a connection leading from the second of said internal chambers in series with each other 30 and discharging into the receiving chamber, a connection feeding into the chamber discharging to the exterior of the buck provided therewith, and opening from the receiving chamber above the level of the liquid therein, and a valve for controlling the flow from the receiving chamber to said chamber discharging to the exterior of the buck provided therewith, substantially as and for the purpose set forth. 35
- 45 22. In a pressing machine, a frame, a bracket mounted on the frame and formed with a receiving chamber, a buck mounted on the bracket and formed with a plurality of chambers, a feed pipe opening into one 50 chamber, a pipe communicating with said chamber, and leading into the receiving chamber, and a valve controlled conduit connecting the receiving chamber and the other chamber of the buck, substantially as and for the purpose set forth. 55
23. In a pressing machine, a frame, a bracket mounted on the frame and formed with a receiving chamber, a buck mounted on the bracket and formed with a pair of 60 heating chambers connected in series and with a third chamber in the form of a conduit separating the pair of chambers, the top wall of the third chamber being perforated, a feed pipe opening into one of the 65 pair of chambers, a conduit connecting the
- other of the pair of chambers and the receiving chamber, and a valve controlled conduit connecting the receiving chamber and the third chamber of the buck, substantially as and for the purpose described. 70
24. In a pressing machine, a frame, a bracket mounted on the frame and formed with a receiving chamber, a buck mounted on the bracket and formed with a plurality of chambers, one of the chambers being in communication with the receiving chamber, a feed pipe opening into said one of the chambers, a valve controlled pipe connecting the receiving chamber and the other chamber of the buck, and a drain pipe leading from said receiving chamber, substantially as and for the purpose described. 75
25. In a pressing machine, a fluid heated buck having a line of perforations opening through its pressing face, and a distributing member overlying the perforations and formed of less width than said pressing face, opposing surfaces of the buck and the distributing member at the lengthwise sides of said member being spaced apart to permit the exit of the heating fluid, substantially as and for the purpose described. 80
26. In a pressing machine, a fluid heated buck having a line of perforations opening through its pressing face, and a distributing member overlying the perforations and formed of less width than said pressing face, the distributing member being provided with a plurality of corrugations in its face opposed to the buck, said corrugations leading to the lengthwise edges of the plate at an angle thereto, and opposing surfaces of the buck and the distributing member at the outer ends of the corrugations being spaced apart to permit the exit of the heating fluid, substantially as and for the purpose described. 85
27. A pressing machine comprising a steam heated buck having its top formed with perforations, and a distributing plate 90 overlying the perforations, the plate being formed with corrugations extending at an angle to each other, substantially as and for the purpose set forth. 100
28. In a pressing machine, a movable buck, a pivoted carriage for the buck, the buck being formed with two chambers in communication with each other, one being located nearer the axis of the carriage than the other, a feed pipe connected to the chamber 115 farthest from the pivot of the carriage, and an outlet pipe connected to the other chamber near the point nearest the axis of the carriage, the pipes extending radially relatively to the axis of the carriage and one 120 being located within the other, substantially as and for the purpose set forth. 125
29. In a pressing machine, the combination of a buck, a pivoted carriage for the buck, two sets of bearing parts arranged at 130

opposite sides of the transverse axis of the buck, said bearing parts permitting the buck to move relatively to the carriage, a plurality of springs for resisting such movement of the buck, two of the springs being arranged at opposite sides of a line extending lengthwise of the buck through one of the sets of bearing parts, and another of the springs being arranged substantially in line with a line 10 extending lengthwise of the buck through the other set of bearing parts, substantially as and for the purpose described.

30. In a pressing machine, the combination of a buck, a pivoted carriage for the buck, three connections for suspending the buck from the carriage, two of said connections being arranged at one side of the transverse axis of the buck and one in advance of the other relatively to the pivotal axis of the carriage, and the other connection being arranged at the other side of said transverse axis and disposed in a line extending lengthwise of the buck between said two of the connections, each of said connections permitting movement of the buck toward the carriage, and including a member for yieldingly resisting such movement, and additional connections between the carriage and the buck for transmitting power from the carriage 25 to the buck and permitting the buck to move relatively to the carriage against the action of said yielding members, substantially as and for the purpose specified.

31. In a pressing machine, a hollow pressing element, a movable carriage for said element, and feed and return conduits connected to the interior of said element, said conduits including sections and a pivoted coupling connecting the sections and having 35 feed and return passages therethrough connected respectively to the feed and the return conduit sections, substantially as and for the purpose described.

32. In a pressing machine, a hollow pressing element, a pivoted carriage for said element, feed and return pipe sections connected to the said element and extending radially relatively to the axis of the carriage, and a pivoted coupling connecting the sections,

the coupling having feed and return passages connected respectively to the feed and return pipe sections and having joints at its opposite ends, one of the joints being arranged in axial alinement with the pivotal axis of said carriage, substantially as and for the purpose specified.

33. In a pressing machine, a hollow buck, a carriage for the buck movable about an axis, the buck being movable relatively to the carriage, an inlet pipe for a heating fluid extending radially from the axis of the carriage and including two sections and a hollow link connecting the sections, the link being pivotally connected to one section at the axis of the carriage and being pivotally connected to the other section, and having a plurality of lengthwise passages and an inlet and outlet for each passage, substantially as and for the purpose described.

34. In a pressing machine, a hollow buck, a pivoted carriage for the buck, the buck being movable relatively to the carriage, and formed with two chambers in communication with each other, an inlet pipe connected to one chamber, an outlet pipe connected to the other chamber, said pipes extending radially relatively to the axis of the carriage, and each including two sections, a coupling connecting the sections comprising unions each being formed with separated axial passages opening respectively through opposite ends of the union and being connected to the contiguous inlet and outlet pipe sections, one union being located in axial alinement with the carriage, side pieces having passages communicating with the respective passages of the unions, the side pieces being articulated to the unions at the ends thereof, and means for clamping the side pieces together, substantially as and for the purpose set forth.

In testimony whereof, I have hereunto signed my name, at Syracuse, in the county of Onondaga, and State of New York, this 1st day of Sept., 1915.

ALLEN CLYMER AUSTIN.
